UNITED STATES PATENT OFFICE.

ALVIN D. PUFFER, OF BOSTON, MASSACHUSETTS.

BEER-COOLER.

SPECIFICATION forming part of Letters Patent No. 230,815, dated August 3, 1880.

Application filed February 25, 1879.

To all whom it may concern:

Be it known that I, ALVIN D. PUFFER, of the city of Boston, county of Suffolk, and State of Massachusetts, have invented certain new and useful Improvements in Apparatus for Cooling Liquids, of which the following is a specification.

This invention relates to improvements in a class of apparatus for reducing the temperature of soda-water or other liquids manufactured by myself, and shown and described in Letters Patent of the United States issued to me on the 6th day of December, 1870, and the 3d day of April, 1877, respectively, the purpose of the invention shown in the first-named patent being to economize the waste of ice used in cooling liquids; and it consists, primarily, in conducting the liquid to be refrigerated through a preliminary or auxiliary series or coil of pipes or cylinders situated within the ice-water which accumulates from the melting of the ice with which the primary cylinders or coolers are packed, or otherwise taking advantage of the low degree of temperature of such ice-water to reduce the temperature of the soda-water or other liquid previous to its entering the primary coolers, which receive cold directly from the ice, while the invention embraced in the second-named patent consists in a new or peculiar manner of conducting soda-water through a cooler or refrigerating apparatus, the purpose of the invention being to thoroughly and effectually carry or force the water, in its passage through a series of cooling-cylinders, against the refrigerated sides or inner surfaces of such cylinders, or to prevent the formation of a central or inner current through the body of water in such cylinders.

In the apparatus shown in both the above-named patents the liquid to be cooled flows through a series of straight cylinders the refrigerating-surfaces of which are of small area compared with the quantity of fluid.

In my present invention I propose to retain the system of circulation shown in my patent first named, and the method of utilizing the melting of the ice and cold-air space shown in the second, the purpose of my present improvement being to compel the liquid, in its passage through the assemblage of tubes, to take a circuitous course in order to expose it a consid-

erable length of time to the cooling effects of the ice or ice-water, in contrast with the method shown in my former patents, in which the liquid found its way through the apparatus by natural laws, without being forced into certain arbitrary directions.

It is also my purpose to so arrange and construct the series of pipes as to strengthen the structure and to put it in condition to better uphold the ice which it carries. To this end I add to the under side of each pipe of the upper series a longitudinal stiffening fin or rib, and I employ with the lower series of pipes a bridge-piece extending transversely of the pipes, which rests on the floor or bottom of the refrigerating-chamber, and upholds the upper pipes, whose ribs rest on the upper edge of the bridge-piece.

Heretofore it has been essential that the blocks of ice should be placed carefully upon the top of the pipes, for fear of injury to the latter. Now, in the employment of the ribs and bridge no special care need be observed in this respect, and the ice may be thrown indiscriminately into the tank containing the pipes.

The drawings accompanying this specification represent, in Figure 1, a perspective view, and in Figs. 2 and 3 horizontal sections of my invention, while Fig. 4 is a cross-section of one of the tubes and its strengthening-rib.

In these drawings, A, B, and C represent a cluster or assemblage of closed cylinders, arranged, by preference, in a longitudinal plane, and connected and communicating at opposite ends with the interiors of two hollow heads, D E. A second cluster of pipes is shown at F G H, and their heads at I J, as arranged below the first, and similarly constructed.

In practice the number of these clusters of pipes, or the number of pipes in each cluster, is not arbitrary, but may be increased or diminished according to circumstances; but I have shown in the present instance, and generally use, two clusters of three pipes each, as being sufficient.

The liquid passing through the apparatus is not permitted a general unobstructed passage through the various pipes and heads, but is led through an indirect course by the following means: Each head has a partition, a, between the mouths of the various pipes, and each al-

ternate partition has a passage, *b*, the arrangement of these passages, as shown in the drawings, being such that the liquid passing through the pipes is compelled to flow through one pipe—say *A*—from the supply-pipe *a'* into and supplying one head—say *D*—then into the adjacent end of the next pipe, *B*, through the latter into the adjacent division of the opposite or first head, *D*, thence return through the next or third pipe, *C*, again into the end division of the head *E*, and flows from the latter downward into the head *I* of the cluster below, and, after circulating through the pipes and heads of this cluster in manner as with the upper cluster, escaping by the outlet-pipe *K* of the head *J*. By this means the liquid is compelled to pursue a circuitous path, which subjects it for a considerable length of time to the action of the ice, and enables its temperature to be reduced to the desired point.

Each pipe of the upper series has upon its under side a longitudinal rib or fin, as shown at *b'* in the drawings, and the lower pipes may be similarly provided, should circumstances require, though in practice I usually omit it.

L in the accompanying drawings represents a bridge arranged transversely of the two clusters of pipes and inclosing the lower series, such bridge resting at bottom upon the floor of the refrigerating-chamber, or the support of the apparatus, whatever it may be, and at its upper edge receiving the ribs of the upper pipes, which rest upon it. The bridge or brace *L* serves to strengthen and support both the upper and lower ranges of pipes, and the number of these bridges is to be determined

by the length of the cylinders. In some instances one will suffice; in others two or more may be required.

The fin or rib *b*, in addition to strengthening and stiffening the cylinder, serves to distribute or spread the water dripping from the cylinder upon the one below, for the reason that the drippings will follow down the rib to its apex, and drop upon the center of the pipe next below, and flow generally over the outer surface of the latter, thus absorbing caloric rapidly from the liquid in such cylinder.

By the arrangement of cylinders and heads as above described the liquid coursing through them is compelled to circulate equally in each, while, by directing the current of the liquid as it issues from each cylinder at right angles against the surface of the head, an ebullition or disturbance takes place, which prevents accumulation of slime within the cylinders.

As the cylinders are disposed in a common horizontal plane, they are equally exposed to the refrigerating action of the ice-water.

I claim—

The series of pipes and their connected and intercommunicating heads, in combination with the intermediate transverse bridge, *L*, the upper series of pipes being formed or provided with longitudinal stiffening ribs or fins, which rest and take their bearing on said bridge, as herein shown and set forth.

A. D. PUFFER.
